UNITED STATES PATENT OFFICE.

JOHN THOMSON, OF BROOKLYN, NEW YORK.

CRANK-BEARING FOR OSCILLATING DISKS.

SPECIFICATION forming part of Letters Patent No. 387,829, dated August 14, 1888.

Application filed February 1, 1888. Serial No. 262,606. (No model.)

To all whom it may concern:

Be it known that I, JOHN THOMSON, a citizen of the United States, and residing in the city of Brooklyn, Kings county, State of New York, have invented certain new and useful Improvements in Crank-Bearings for Oscillating Disks, of which the following is a specification.

This invention relates to an improved form of crank-bearing for controlling the action of oscillating disks.

In the drawings, Figure 1 shows the device in elevation and cross-section, and the application thereof may be assumed as that of a water-meter or a blower, a pump or a steam-engine—such, for instance, as is illustrated in my patent, No. 375,023. Fig. 2 is a top plan view.

The object of the invention is to obviate the false thrust due to the action of cylindrical bearings. This is avoided by employing a rotating crank-block, the arrangement and construction being such that the acting surfaces and bearings therefor are parallel with the central axis of the disk-shaft or at a right angle to the line of inward and outward thrust thereof.

In the illustration, 5 represents the disk-chamber; 6, the ball; 7, the sockets; 8, the disk, and 9 the disk-shaft.

The action of the disk is of course well known, and here requires no special description, being fully set forth in my patent above referred to, except to observe that the constant oscillation of the disk causes the disk-shaft to travel in a circle, as C, or conversely, the shaft being caused to travel in a circle will produce oscillating action in the disk. In either instance, however, the power must be received or transmitted through the disk-shaft. The chief peculiarity of the motion of the disk-shaft, and to which this, my invention, particularly refers, is that its axis, line 10, beginning at the center 11 of the ball for each oscillation of the disk, describes a true cone; therefore the thrust of the disk-shaft is at less than a right angle to the central axis, 12, to or from which the said thrust is transmitted or received. The consequence of this is that with any of the arrangements heretofore used—such, for instance, as are shown in Reuleaux's

Kinematics of Machinery, edition of 1876, plates 28 and 29—there is a wedging action tending to cramp the shafts and adding friction to the motion of the ball and disk. The 55 reason for this wedging action, as already intimated, is that the bearing (or bearings) that resists the thrust of the disk-shaft is at less than a right angle. This I entirely avoid by means of the rotating crank-block 13; the conical bearing 14 therefor formed in the flange 15, and the central fixed conical bearing, 16, which projects inward toward the ball from the frame or plate 17, the latter being separately secured to the disk-chamber. 60

The necessary form of the crank-block and its bearings to effect the desired relief is determined by the angle of the disk-shaft. Thus in the illustration the angle of the disk-shaft is twenty degrees from the vertical. The bearing 18 being first provided, the outer surface, 19, and the inner surface, 20, are then simply formed parallel to the bore of the disk-shaft bearing, and in like manner the bearings 14 and 16 are constructed. The result of this is 65 that any effect tending to thrust the disk-shaft outward will be resisted by the bearing at 19, which is at a right angle to the line of thrust of the disk-shaft, and also any effort to thrust the disk-shaft inward will be resisted at 20, 70 which is also at a right angle to the line of thrust of the disk-shaft, as indicated, respectively, by arrows e and i. Thus, no dynamic effect can be produced by the disk-shaft tending either to cramp the action as a whole or 75 to add to the friction of rotation. In other words, the entire effort, if from the disk, is to rotate the crank-block, or, if from the crank-block, to oscillate the disk.

The central shaft, 21, will be secured to the 80 crank-block in a manner necessary to properly effect the intended duty. It is here shown as being screwed thereto, as at 22.

The lower face of the crank-block is adapted to rest upon the shoulder 23, formed at the 85 bottom of the bearing 14. There is thus no tendency for the crank-block to slip down and wedge.

It is evident that two crank-blocks may be employed where the duty is severe—one on 90 each side of the disk—or a duplicate of that shown on the upper side of the disk, to be situ-

ated below the disk and opposite that shown in the illustration; also, that the crank-block need not necessarily be a complete circular ring, as a segment thereof may be used.

5 I claim—

1. In an oscillating disk-action, the combination of the disk-shaft, rotating crank-block, and outer and inner bearings, 14 16, the acting surfaces of said block and bearings being 10 parallel with the said disk-shaft.

2. A rotating crank-block for oscillating disk-actions, having a bore for the disk-shaft and having bearings formed parallel to the bore at a right angle to the lines of thrust of 15 said disk-shaft.

3. The combination of the rotating crank-block having a bore for a shaft and bearing-faces parallel to the bore, the conical bearing 14 for the exterior faces of the block, and a conical bearing, 16, for the interior faces of the 20 block.

In testimony whereof I have signed my name to this specification in the presence of two subscribing witnesses.

JOHN THOMSON.

Witnesses,

F. L. FREEMAN,
A. E. T. HANSMANN.
